REPEATING FIREARM

Carl G. Swebilius, Hamden, Conn.

Application March 5, 1943, Serial No. 478,057

12 Claims. (Cl. 42-3)

The present invention relates to improvements in repeating firearms, i. e., firearms which are provided with magazines from which ball-cartridges may be sequentially fed to the cartridge-chamber of the firearm for being fired. More particularly, the present invention relates to improvements in the action-slide and associated elements of the firearm-structure, as will appear from the following.

One of the objects of the present invention is to provide a superior repeating firearm in which simple, reliable and effective means is provided for alternately covering and uncovering the ejection-opening thereof to respectively exclude foreign matter from the mechanism and to permit the ejection of cartridge-cases.

Another object of the present invention is to provide a superior firearm-structure of the character referred to which includes a receiver having an ejection-opening and an action-slide slidably coupled to the said receiver so as to alternately cover and uncover the ejection-opening of the receiver, while at the same time discharging the function of operating a breech-bolt.

A further object of the present invention is to provide a repeating firearm having an action-slide mounted for reciprocation adjacent a receiver and in which a superior construction and arrangement is employed for guiding and retaining the said action-slide with respect to the said receiver.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1a is a broken view partly in side elevation and partly in vertical central-longitudinal section of the intermediate portion of a firearm-structure embodying the present invention and in which the action-slide, breech-bolt and associated parts are shown in their forward positions;

Fig. 1b is a similar view of the portion of the firearm immediately forward of the portion shown in Fig. 1a;

Fig. 2 is a view similar to Fig. 1a but showing the action-slide and associated parts in their rearmost positions;

Fig. 3 is a broken top or plan view of the portion of the firearm immediately above the box-magazine with the parts in the same positions in

which they are shown in Fig. 1a, but with the action-slide partly in section;

Fig. 4 is a transverse sectional view taken on the line 4-4 of Fig. 1a;

Fig. 5 is a similar view taken on the line 5-5 of Fig. 1a;

Fig. 6 is a view similar to Fig. 5 but omitting the stock and with the guard-collar shown in position to permit the removal of the action-slide from the receiver;

Fig. 7 is a view in side elevation of the receiver and the rear portion of the barrel;

Fig. 8 is a broken detailed sectional view taken on the line 8-8 of Fig. 7;

Fig. 9 is a perspective view of the guard-collar detached and looking mainly toward the front face thereof;

Fig. 10 is a view in inside elevation of the action-slide, detached; and

Fig. 11 is a front-end view thereof.

The particular repeating firearm herein chosen for purposes of illustrating one embodiment of the present invention, is of the gas-operated self-loading type. The said firearm includes, in the

main, a frame 15, a receiver 16, a barrel 17, a stock 18 and a barrel-cover 19. The gas-operated self-loading firearm shown also includes a breech-bolt 20, an action-slide 21, a connecting-link 22, a reciprocating gas-operated piston 23, and a cylinder-fitting 24.

With the exception of the stock 18 and barrel-cover 19, the parts above referred to are preferably formed of high-grade steel, while the said parts 18 and 19 are preferably formed of wood or other suitable heat-insulating and shock-absorbing material. The frame 15 above referred to is mainly of plate-like form and is formed on its lower edge with a loop-like trigger-guard 25 extending around a trigger 26 which controls the firing-mechanism of the firearm in any suitable manner not requiring detailed description herein.

The frame 15 is rigidly secured to the stock 18 in any suitable manner such, for instance, as by a bolt 27, while the said frame 15 and receiver

16 are detachably secured together in any suitable manner not requiring detailed description herein, so that, in effect, the two last-mentioned elements may be said to constitute a frame-structure. The barrel 17 is rigidly coupled at its rear

end with the forward end of the receiver 16 by being provided with an exteriorly-threaded stem 17a screwed into a threaded passage 16a in the forward end of the receiver 16. The said receiver is generally of cylindrical form exteriorly and is provided in its interior with an axial passage 28.

in which the breech-bolt 20 both reciprocates and oscillates and which communicates at its forward end with the threaded passage 16a. The rear end of the passage 28 just referred to is closed by a standing-breech 29 forming part of the upper rear-portion of the frame 15.

The action-slide 21 is preferably formed of two major parts for purposes of economy of manufacture, namely, a sheet-metal shell 30 of circular form in cross section, and a relatively-heavy body 31 brazed or otherwise rigidly united to the outer surface of the said shell 30. Adjacent its rear end and hence about midway the length of the action-slide 21 viewed as a whole, the body 31 of the said action-slide is provided with an outwardly-projecting operating-handle 32 by means of which the said action-slide and hence the breech-bolt 20 may be manually operated when desired.

About midway of its length, the action-slide 21 is formed with a downwardly-opening recess 33 which receives a coupling-lug 34 projecting upwardly from the rear end of the connecting-link 22 before referred to. Adjacent and intersecting its recess 33, the action-slide 21 is formed with a horizontal slot 35 which also intersects the exterior periphery of the said action-slide both to the front and to the rear of the operating-handle 32 thereof.

The coupling-lug 34 at the rear end of the connecting-link 22, is releasably held in place in the recess 33 in the action-slide 21, by a pivotal coupling-lever 36 installed in the slot 35 of the said action-slide (as shown in Fig. 3) and acting as releasable coupling-means for the rear end of the connecting-link 22 in a manner more fully shown and described in my co-pending application Serial No. 478,058, filed March 5, 1943.

At its forward end, the connecting-link 22 is formed with a coupling-lug 37 extending downwardly through a clearance-slot 38 formed in the upper portion of the cylinder-fitting 24. The said coupling-lug 37 extends into coupled engagement with the rear portion of the piston 23 reciprocating in the longitudinal piston-chamber 40 formed in the cylinder 24, as is shown in Fig. 1b.

At its forward end, the piston-chamber 40 just above referred to is connected by means of aligned gas-passages 41 and 42 to the bore 43 of the barrel 17 and respectively formed in the forward portion of the cylinder-fitting 24 and the adjacent portion of the barrel 17, as is clearly shown in Fig. 1b.

The piston 23 and hence, also, the parts connected thereto, are yieldingly urged forwardly by a helical breech-closing spring 44 having its forward end seated within the recessed rear-end of the piston 23 against the coupling-lug 37 and having its rear portion encircling a guide-rod 45. The rear end of the breech-closing spring 44 thrusts rearwardly against a bracket 46 (Fig. 1a) carrying the guide-rod 45 and releasably attached to the forward under-face of the receiver 16 immediately forwardly of the box-magazine 47.

Returning now to the receiver 16, it will be noted that the said receiver is of substantially-cylindrical form exteriorly and is formed at substantially-diametrically-opposite points with one of two longitudinal guide-grooves 48 and 49 which extend parallel with each other and with the longitudinal axis of the receiver 16. The said guide-grooves 48 and 49 terminate at their rear a short distance forwardly of the rear end of the

receiver 16, and at their forward ends both of the said guide-grooves 48 and 49 intersect the forward face of the said receiver.

The guide-grooves 48 and 49 in the receiver 16 respectively receive with a free sliding fit, guide-ribs 50 and 51 extending inwardly from the action-slide 21 at each of the respective opposite side-edges thereof, as is especially well shown in Figs. 4, 5, 6 and 11. Preferably, the guide-ribs 50 and 51 are formed by bending the respective opposite side-edges of the sheet-metal shell 30 of the action-slide 21 prior to the brazing or other securing of the said shell to the body 31 in order to form a unitary action-slide such as 21. As thus constructed and arranged, the coaction of the surfaces of the guide-grooves 48 and 49 with the respective guide-ribs 50 and 51 serve to guide the reciprocating movement of the action-slide 21 and hold the same against lateral separation from the receiver 16.

Immediately above the box-magazine 47, the receiver 16 is formed with an ejection-opening 52 leading upwardly from the axial passage 28 in the said receiver to the outer periphery of the latter, to permit the ejection of cartridge-cases therethrough when the breech-bolt 20 is moved rearwardly, following the discharge of the firearm, in a manner well understood in the art. Formed in the upper right side of the receiver 16 and leading rearwardly from the rear end of the ejection-opening 52 therein, is a longitudinal clearance-slot 53 adapted to receive with a sliding fit a lug 54 laterally projecting from the forward end of the breech-bolt 20. Formed in the receiver 16 just forwardly of and communicating with the ejection-opening 52 therein, is a locking-notch 55 in which the lug 54 of the breech-bolt 20 is normally located when the said breech-bolt is in its breech-closing position.

The outer end of the lug 54 of the breech-bolt 20 projects into a cam-recess 56 (Fig. 1a) formed in the inner face of the action-slide 21 and acting on the said lug 54 to both turn the same to unlock and lock the breech-bolt and to reciprocate the said breech-bolt in a manner well understood in the art and broadly similar to the manner in which the breech-bolt of the well-known Garand military rifle is operated.

As will be seen especially well by reference to Fig. 8, the exteriorly-threaded stem 17a at the rear end of the barrel 17 extends forwardly of the front face of the receiver 16 when the said stem is firmly interlocked in the threaded passage 16a in the said receiver. Mounted upon the forward portion of the stem 17a immediately forwardly of the front face of the receiver 16, is an internally-threaded guard-collar 58. The said guard-collar has its rear face normally seated against the forward face of the receiver 16 but is rotatable from such position for purposes as will hereinafter appear.

In its rear face the guard-collar 58 above referred to, is formed at substantially diametrically-opposite points respectively with two detent-pockets 59 and 60 alternately receiving the rounded forward end of a detent-plunger 61. The said detent-plunger 61 is mounted for reciprocation in a forwardly-opening pocket 62 formed in the left side of the forward end of the receiver 16 and opening through the forward face thereof, as is especially well shown in Fig. 8. The said detent-plunger 61 is urged forwardly by a helical detent-spring 63 interposed between the rear end of the said detent-plunger and the bottom wall 75 of the pocket 62.

On what is normally its right side, the guard-collar 58 is formed with an eccentric stop-nose 64 projecting outwardly therefrom and of about 90° circumferential extent. The remainder of the circumferential extent of the guard-collar 58 is cylindrically contoured and substantially corresponds in diameter to the diameter of the cylindrically-contoured forward portion of the receiver 16. Immediately below its stop-nose 64, the said guard-collar 58 is formed on its periphery with a clearance-groove 65 which is normally slightly out of register with the guide-groove 48 in the right side of the receiver 16. Substantially diametrically opposite the clearance-groove 65 just referred to, the guard-collar 58 is also formed on its periphery with a second clearance-groove 66 also normally slightly out of register with the adjacent guide-groove 48 in the periphery of the receiver 16. Both of the aforesaid clearance-grooves 65 and 66 extend in parallelism with the longitudinal axis of the receiver 16 and hence in parallelism with the guide-grooves 48 and 49 thereof.

Normally, the guard-collar 58 is held in its guard position in which it is shown in Figs. 1a, 2, 3, 5, 7 and 8, by the entry of the forward end of the detent-plunger 61 into its detent-pocket 60. In this position, the respective clearance-grooves 65 and 66 of the guard-collar 58 are out of registry with the guide-grooves 48 and 49 of the receiver 16, so that the forward movement of the action-slide 21 is limited by the engagement of the edge of the guide-ribs 50 and 51 with the rear face of the said guard-collar 58. Under the conditions just described, the stop-nose 64 is interposed in the path of forward movement of the action-slide 21 and would, by itself, normally limit the forward travel of the said action-slide.

Should it be desired for any reason to dismount the action-slide 21 from the receiver 16, the unit comprising the receiver and barrel should first be detached from the stock and then the rear end of the connecting-link 22 should be uncoupled from the action-slide 21 by rocking the coupling-lever 36 and either totally removing or displacing the said connecting-link sufficiently to clear it from the path of movement of the stop-nose 64. The breech-bolt 20 may now be disconnected from the action-slide 21 by moving the said breech-bolt to the limit of its rearward movement to thereby bring its relatively-slender forward end into the relatively large-diametered rear portion of the axial passage 28 in the receiver 16. The forward end of the breech-bolt may now be swung laterally to disengage its lug 54 from the cam-recess 56 in the action-slide 21. The guard-collar 58 may now be rotated substantially one-half turn on the shank 17a of the barrel 17 in a counter-clockwise direction (as viewed from the front) until the detent-pocket 59 of the guard-collar is brought into registration with the detent-plunger 61. When thus shifted, and yieldingly held by the detent-plunger 61, the clearance-grooves 65 and 66 on the periphery of the said guard-collar will be brought into registration respectively with the guide-grooves 49 and 48 of the receiver 16 and the stop-nose 64 will be shifted into a position clear of the longitudinal path of movement of the action-slide 21. By the turning movement of the guard-collar 58 as above described, the same will be brought into the position in which it is shown in Fig. 6.

Now the action-slide 21 may be slid forwardly until its rear end passes completely clear of the

forward face of the guard-collar 58, whereupon the action-slide is completely free of attachment to the firearm-structure.

When the guard-collar 58 is in its normal position as is especially well shown in Figs. 2 and 5, its forward face is in position to be engaged by the rear face of a stop-finger 67 upstanding from the connecting-link 22, for purposes as will hereinafter appear.

10 When the firearm is discharged, gas under pressure will pass from the bore 43 of the barrel 17 downwardly through the aligned gas-passages 42 and 41 and thence into the forward end of the piston-chamber 40 of the cylinder-fitting 24. This gas will act on the forward end of the piston 23 to drive the said piston violently rearwardly. The rearward movement of the piston 23 will similarly move the connecting-link 22 rearwardly and hence will also rearwardly move 15 the action-slide 21 which is coupled to the rear end of the said connecting-link as before described. The rearward movement of the action-slide 21 will cause the said action-slide to act through the intermediary of its cam-recess 56 and the lug 54 of the breech-bolt 20, to first turn and then rearwardly retire the said breech-bolt and thus effect the extraction and ejection of the just-fired cartridge in a manner well understood in the art. The ejection of the just-fired cartridge will occur through the ejection-opening 52 of the receiver 16 which becomes uncovered as a result of the rearward travel of the said action-slide.

20 The parts will continue their rearward travel 25 against the tension of the breech-closing spring 44 until they assume substantially the positions in which they are shown in Fig. 2. It will be noted by reference to Fig. 2 that the rearward movement of the connecting-link 22 has been 25 checked by the engagement of its stop-finger 67 with the forward face of the guard-collar 58. It will also be noted that the forward edge of the action-slide 21 has moved to a position substantially flush with the rear end of the ejection-opening 52 in the receiver 16.

25 Normally and immediately after having 30 reached the positions in which they are shown in Fig. 2, the parts will be restored to their forward positions under the urge of the breech-closing spring 44. This return or forward movement of the parts will cause the breech-bolt 20 to remove a fresh cartridge from the box-magazine 47 and insert the same into the cartridge-chamber of the firearm in any suitable manner 35 well understood in the art.

35 During its reciprocating movement, from the position in which it is shown in Fig. 1a to the position in which it is shown in Fig. 2 and vice versa, the action-slide 21 is accurately guided by 40 the sliding of its respective guide-ribs 50 and 51 in the guide-grooves 48 and 49 of the receiver 16.

45 From the foregoing it will be seen that the action-slide 21 when in its normal forward position, completely covers not only the ejection-opening 52 in the receiver 16, but also covers the clearance-slot 53 and the locking-notch 55 of the said receiver to thereby effectively exclude dirt, water and other foreign matter from entry into the interior of the receiver.

50 The invention may be carried out in other specific ways than those herein set forth without departing from the spirit and essential characteristics of the invention, and the present embodiments are, therefore, to be considered in all respects as illustrative and not restrictive, and

all changes coming within the meaning and equivalency range of the appended claims are intended to be embraced therein.

I claim:

1. A repeating firearm-structure including in combination: a frame-structure having an ejection-opening therein; a breech-bolt movable in the said frame-structure; a barrel projecting forwardly from the said frame-structure; an action-slide operatively connected to the breech-bolt for moving the same and mounted on the said frame-structure for movement with respect thereto, the said action-slide having a forward position in which it covers the ejection-opening in the said frame-structure and also having a rearward position in which the said action-slide uncovers the said ejection-opening; spring-means urging the said action-slide into its forward position; and a rotary stop-member mounted adjacent the forward end of the said frame-structure and having stop-means thereon normally projecting into the path of forward travel of the said action-slide, the said stop-member being rotatable in a direction transverse of the firearm-structure to shift the stop-means thereof into and out of the path of forward movement of the said action-slide.

2. A repeating firearm-structure including in combination: a frame-structure having an ejection-opening therein; a breech-bolt movable in the said frame-structure; a barrel projecting forwardly from the said frame-structure; an action-slide operatively connected to the breech-bolt for moving the same and mounted on the said frame-structure for movement with respect thereto, the said action-slide having a forward position in which it covers the ejection-opening in the said frame-structure and also having a rearward position in which the said action-slide uncovers the said ejection-opening; spring-means urging the said action-slide into its forward position; and a rotary stop-member mounted on the rear portion of the said barrel adjacent the forward end of the said frame-structure for turning movement in a direction transverse of the firearm-structure, the said stop-member having stop-means thereon normally projecting into the path of forward travel of the said action-slide and movable out of the path of the said action-slide when the said stop-member is turned on the said barrel.

3. A repeating firearm-structure including in combination: a frame-structure having an ejection-opening therein; a breech-bolt movable in the said frame-structure; a barrel projecting forwardly from the said frame-structure and having external threads thereon located adjacent the forward end of the said frame-structure; an action-slide operatively connected to the said breech-bolt for moving the same and mounted on the said frame-structure for movement with respect thereto, the said action-slide having a forward position in which it covers the ejection-opening in the said frame-structure and also having a rearward position in which the said action-slide uncovers the said ejection-opening; spring-means urging the said action-slide into its forward position; and an internally-threaded ring-like stop-member mounted on the threaded rear portion of the said barrel for turning movement thereon in a direction transverse of the firearm-structure, the said stop-member having stop-means thereon normally projecting into the path of forward travel of the said action-slide and movable out of the path of the said action-

slide when the said stop-member is turned on the said barrel.

4. A repeating firearm-structure including in combination: a frame-structure having an ejection-opening therein; a breech-bolt movable in the said frame-structure; a barrel projecting forwardly from the said frame-structure; an action-slide operatively connected to the breech-bolt for moving the same and mounted on the said frame-structure for movement with respect thereto, the said action-slide having a forward position in which it covers the ejection-opening in the said frame-structure and also having a rearward position in which the said action-slide uncovers the said ejection-opening; spring-means urging the said action-slide into its forward position; a rotary stop-member mounted adjacent the forward end of the said frame-structure and having stop-means thereon normally projecting into the path of forward travel of the said action-slide, the said stop-member being rotatable in a direction transverse of the firearm-structure to shift the stop-means thereof into and out of the path of forward movement of the said action-slide; and detent-means for releasably holding the said stop-member in position to interpose its stop-means in the path of the said action-slide and also for releasably holding the said stop-member in a position wherein its stop-means is out of the path of the said action-slide.

5. A repeating firearm-structure including in combination: a receiver formed on its exterior with two parallel guide-grooves extending longitudinally of the said receiver and laterally spaced from each other, the said receiver also being formed with an ejection-opening; a breech-bolt movable in the said receiver; a barrel projecting forwardly from the said receiver; an action-slide operatively connected to the said breech-bolt and provided with two parallel guide-ribs each sliding in one of the guide-grooves in the said receiver, the said action-slide having a forward position in which it covers the ejection-opening in the said receiver and also having a rearward position in which the said action-slide uncovers the said ejection-opening; spring-means urging the said action-slide into its forward position; and a rotary stop-member mounted adjacent the forward end of the said receiver and having stop-means thereon normally projecting into the path of forward travel of the said action-slide, the said stop-member being rotatable in a direction transverse of the firearm-structure to shift the stop-means thereof into and out of the path of forward movement of the said action-slide.

6. A repeating firearm-structure including in combination: a receiver formed on its exterior with two parallel guide-grooves extending longitudinally of the said receiver and laterally spaced from each other, the said receiver also being formed with an ejection-opening; a breech-bolt movable in the said receiver; a barrel projecting forwardly from the said receiver; an action-slide operatively connected to the said breech-bolt and provided with two parallel guide-ribs each sliding in one of the guide-grooves in the said receiver, the said action-slide having a forward position in which it covers the ejection-opening in the said receiver and also having a rearward position in which the said action-slide uncovers the said ejection-opening; spring-means urging the said action-slide into its forward position; and a rotary stop-member mounted on the rear portion of the said barrel adjacent the forward end of the said receiver for turning move-

ment in a direction transverse of the firearm-structure, the said stop-member having stop-means thereon normally projecting into the path of forward travel of the said action-slide and movable out of the path of the said action-slide when the said stop-member is turned on the said barrel.

7. A repeating firearm-structure including in combination: a receiver formed on its exterior with two parallel guide-grooves extending longitudinally of the said receiver and laterally spaced from each other, the said receiver being formed with an ejection-opening; a breech-bolt movable in the said receiver; a barrel projecting forwardly from the said receiver and having external threads thereon located adjacent the forward end of the said receiver; an action-slide operatively connected to the said breech-bolt and provided with two parallel guide-ribs each sliding in one of the guide-grooves in the said receiver, the said action-slide having a forward position in which it covers the ejection-opening in the said receiver and also having a rearward position in which the said action-slide uncovers the said ejection-opening; spring-means urging the said action-slide into its forward position; and an internally-threaded ring-like stop-member mounted on the threaded rear portion of the said barrel for turning movement thereon in a direction transverse of the firearm-structure, the said stop-member having stop-means thereon normally projecting into the path of forward travel of the said action-slide and movable out of the path of the said action-slide when the said stop-member is turned on the said barrel.

8. A repeating firearm-structure including in combination: a receiver formed on its exterior with two parallel guide-grooves extending longitudinally of the said receiver and laterally spaced from each other, the said receiver also being formed with an ejection-opening; a breech-bolt movable in the said receiver; a barrel projecting forwardly from the said receiver; an action-slide operatively connected to the said breech-bolt and provided with two parallel guide-ribs each sliding in one of the guide-grooves in the said receiver, the said action-slide having a forward position in which it covers the ejection-opening in the said receiver and also having a rearward position in which the said action-slide uncovers the said ejection-opening; spring-means urging the said action-slide into its forward position; a rotary stop-member mounted adjacent the forward end of the said receiver and having stop-means thereon normally projecting into the path of forward travel of the said action-slide, the said stop-member being rotatable in a direction transverse of the firearm-structure to shift the stop-means thereof into and out of the path of forward movement of the said action-slide; and detent-means for releasably holding the said stop-member in position to interpose its stop-means in the path of the said action-slide and also for releasably holding the stop-member in a position wherein its stop-means is out of the path of the said action-slide.

9. A repeating firearm-structure including in combination: a cylindrically-contoured receiver formed on its exterior with two parallel guide-grooves extending longitudinally of the said receiver and laterally spaced from each other, the said cylindrically-contoured receiver also being formed with an ejection-opening; a breech-bolt movable in the said receiver; a barrel projecting forwardly from the said receiver; an action-slide operatively connected to the said breech-bolt and

having a cylindrically-contoured inner face substantially conforming to and bearing upon the cylindrical contour of the said receiver, the said action-slide being provided with two parallel guide-ribs each sliding in one of the guide-grooves in the said cylindrically-contoured receiver, the said action-slide having a forward position in which it covers the ejection-opening in the said receiver and also having a rearward position in which the said action-slide uncovers the said ejection-opening; spring-means urging the said action-slide into its forward position; and a rotary stop-member mounted adjacent the forward end of the said receiver and having stop-means thereon normally projecting into the path of forward travel of the said action-slide, the said stop-member being rotatable in a direction transverse of the firearm-structure to shift the stop-means thereof into and out of the path of forward movement of the said action-slide.

10. A repeating firearm-structure including in combination: a cylindrically-contoured receiver formed on its exterior with two parallel guide-grooves extending longitudinally of the said receiver and laterally spaced from each other, the said cylindrically-contoured receiver also being formed with an ejection-opening; a breech-bolt movable in the said receiver; a barrel projecting forwardly from the said receiver; an action-slide operatively connected to the said breech-bolt and having a cylindrically-contoured inner face substantially conforming to and bearing upon the cylindrical contour of the said receiver, the said action-slide being provided with two parallel guide-ribs each sliding in one of the guide-grooves in the said cylindrically-contoured receiver, the said action-slide having a forward position in which it covers the ejection-opening in the said receiver and also having a rearward position in which the said action-slide uncovers the said ejection-opening; spring-means urging the said action-slide into its forward position; and a rotary stop-member mounted adjacent the forward end of the said receiver and having stop-means thereon normally projecting into the path of forward travel of the said action-slide, the said stop-member being rotatable in a direction transverse of the firearm-structure to shift the stop-means thereof into and out of the path of forward movement of the said action-slide.

11. A repeating firearm-structure including in combination: a cylindrically-contoured receiver formed on its exterior with two parallel guide-grooves extending longitudinally of the said receiver and laterally spaced from each other, the said cylindrically-contoured receiver also being formed with an ejection-opening; a breech-bolt movable in the said receiver; a barrel projecting forwardly from the said receiver and having external threads thereon located adjacent the forward end of the said receiver; an action-slide operatively connected to the said breech-bolt and having a cylindrically-contoured inner face substantially conforming to and bearing upon the cylindrical contour of the said receiver, the said action-slide being provided with two parallel guide-ribs each sliding in one of the guide-grooves in the said cylindrically-contoured receiver, the said action-slide having a forward position in which it covers the ejection-opening in the said receiver and also having a rearward position in which the said action-slide uncovers the said ejection-opening; spring-means urging the said action-slide into its forward position; and an in-

ternally-threaded ring-like stop-member mounted on the threaded rear portion of the said barrel for turning movement thereon in a direction transverse of the firearm-structure, the said stop-member having stop-means thereon normally projecting into the path of forward travel of the said action-slide and movable out of the path of the said action-slide when the said stop-member is turned on the said barrel.

12. A repeating firearm-structure including in combination: a cylindrically-contoured receiver formed on its exterior with two parallel guide-grooves extending longitudinally of the said receiver and laterally spaced from each other, the said receiver also being formed with an ejection-opening; a breech-bolt movable in the said receiver; a barrel projecting forwardly from the said receiver; an action-slide operatively connected to the said breech-bolt and provided with two parallel guide-ribs each sliding in one of the guide-grooves in the said receiver, the said action-slide having a cylindrically-contoured inner face sub-

stantially conforming to and bearing upon the cylindrical contour of the said receiver, the said action-slide having a forward position in which it covers the ejection-opening in the said receiver and also having a rearward position in which the said action-slide uncovers the said ejection-opening; spring-means urging the said action-slide into its forward position; a rotary stop-member mounted adjacent the forward end of the said receiver and having stop-means thereon normally projecting into the path of forward movement of the said action-slide, the said stop-member being rotatable in a direction transverse of the firearm-structure to shift the stop-means thereof into and out of the path of forward movement of the said action-slide; and detent-means for releasably holding the said stop-member in position to interpose its stop-means in the path of the said action-slide and also for releasably holding the said stop-member in a position wherein its stop-means is out of the path of the said action-slide.
